UNITED STATES PATENT OFFICE.

JOSEPH L. POTTER, OF INDIANAPOLIS, INDIANA.

EXCAVATING AND CONVEYING APPARATUS.

1,142,457.

Specification of Letters Patent.

Patented June 8, 1915.

Application filed February 3, 1913. Serial No. 745,888.

To all whom it may concern:

Be it known that I, JOSEPH L. POTTER, a citizen of the United States, residing at Indianapolis, in the county of Marion and 5 State of Indiana, have invented a new and useful Excavating and Conveying Apparatus, of which the following is a specification, reference being had to the accompanying drawings, and to the letters and figures 10 of reference marked thereon.

This invention relates to apparatus for excavating or hoisting or for conveying substances or earth from excavations, the invention having reference more particularly 15 to portable or movable machinery or apparatus adapted for excavating trenches for sewers and for conveying the earth removed from the trenches and dumping it back into the trenches after completion of portions 20 of the masonry or sewer structure.

An object of the invention is to provide improved excavating and conveying apparatus of such construction as to enable a small number of men to carry on the work 25 of sewer construction expeditiously and economically, especially by the use of a drag bucket or scoop for excavating and hoisting the earth, a particular object of the invention being to provide improved means that 30 shall operate automatically to guide the bucket or scoop as the excavating proceeds downward into the earth and also as the work advances longitudinally of the line of 35 the trench.

Another object of the invention is to provide improved means for discharging the earth from the excavating scoop or drag bucket; a further object being to provide improved means and arrangement thereof 40 for receiving and conveying the earth away from the dumping bucket or scoop.

A still further object is to provide improved apparatus for operating the excavating implement, and also improved means 45 for operating the conveying car preferably employed for delivering the earth back into the trench.

With the above mentioned and other objects in view the invention consists in improved excavating and conveying apparatus comprising an engine car provided with an adjustable head sheave and also a relatively long reach-arm that is supported at its free end on the ground, either on the surface 50 level of the ground or on the bottom of the

trench being excavated, the reach-arm carrying a tail sheave required for drawing a drag bucket or excavating scoop back into the trench after having been drawn out loaded, the invention comprising also improvements in various parts of the apparatus such as the scoop and means for operating it, in a conveying car and means for operating it, and in a trestle for supporting the conveying car; and the invention 60 consists further in the novel parts and in the combinations and arrangements of parts as hereinafter particularly described and claimed.

Referring to the drawings, Figure 1 is a 70 side elevation of the improved excavating and conveying apparatus partially broken away and shown in relation to a section of trench; Fig. 2, a top plan of the improved apparatus; Fig. 3, a sectional elevation approximately on the line A A in Fig. 1; Fig. 4, a sectional elevation approximately on the line B B in Fig. 1; Fig. 5, a fragmentary sectional elevation approximately on the line C C in Fig. 3; Fig. 6, a fragmentary 75 horizontal section approximately on the line D D in Fig. 5 with the frame of the head sheave in lowered position and appearing as a top plan; Fig. 7, a perspective view of a winding drum preferably employed for 80 operating the excavating implement; Fig. 8, a side elevation of an improved dumping conveying car shown in dumping position; Fig. 9, a fragmentary section of the improved winding drum and its driving bull 85 wheel or pulley; Fig. 10, a fragmentary section approximately on the line E E in Fig. 5; Fig. 11, a perspective view of the head 90 sheave and its frame; Fig. 12, a fragmentary side elevation of the improved trestle 95 shown as adjusted for an inclined ground surface; Fig. 13, a side elevation of the improved bull wheel partially in section; Fig. 14, a fragmentary perspective view of portions of the improved trestle; and Fig. 15, 100 a perspective view of a reach-arm for carrying the tail sheave required for drawing the excavating implement back onto the bottom of the trench.

Throughout the different figures of the drawings like reference characters indicate like elements or features of construction herein referred to.

In the drawings the numeral 1 indicates 105 the ground or earth and 2 an excavation 110

therein; 3, 3' and 4 the sheathing in the trench, 5, 5' and 6, 6' the horizontal timbers, and 7, 7' the screw braces for supporting the sheathing to prevent caving in of the sides of the excavation; 8 and 8' indicating the longitudinal track stringers, and 9 and 9' the track rails on the stringers that are usually employed.

Practically carrying out the objects of the invention, a suitable engine car is provided which preferably comprises two side sills 10 and 10' and two intermediate sills 11 and 11' provided with a platform 12 to constitute a main frame which is mounted on two axles 13 and 14 provided with wheels 15 and 15' mounted on the track rails to enable the engine car to be readily moved forward as the work proceeds. The engine car includes also an upright frame which preferably comprises two side posts 16 and 16' and also two intermediate posts 17 and 17' erected on the horizontal frame at a relatively short distance forward of the rear end thereof, two braces 18 and 18' being secured to the upright frame and also to the forward portion of the horizontal or main frame of the car. The upright frame preferably is provided also with rear braces 19 and 19' and transverse beams 20 and 21. The engine car is provided with two upright guide bars 22 and 22' that are mounted on the rear end portions of the intermediate sills 11 and 11' and serve as frame posts to support two frame members 23 and 23' that are secured to the tops of the guide bars respectively and also to the intermediate posts 17 and 17' adjacent the beam 20. A shaft 24 is mounted upon the said frame members and supports a guide sheave 25. In order to adjustably support a head sheave for the hoisting cable a suitable frame is provided which preferably comprises two slides 26 and 26' to which a cross bar 27 and two arms 28 and 28' are secured, the slides being arranged to slide vertically in contact with and be guided by the guide bars 22 and 22' which preferably are of channel section, an end bar 29 preferably being secured to the end portions of the arms, and two braces 30 and 30' are secured to the slides and also to the end portions of said arms, the arms supporting a shaft 31 on which is a sheave 32. Said braces 30 and 30' are inclined and the under sides thereof have each a shoulder 33 facing downwardly, which shoulder may be formed by notching the braces to receive the bail of the drag bucket and prevent the latter from turning around while being hoisted. Suitable provision preferably is made for latching the frame in lowered position so as to prevent the head sheave from moving upward from the desired position, and this is accomplished preferably by means of a shaft 34 mounted on the slides 26 and 26' and pro-

vided with upwardly extending dogs 35 and 35' and also an operating arm 36 that extends rearwardly below the shaft 31 so as to be engaged and lifted by the ascending bucket bail. The guide bars are provided with projections 37 and 37' to be engaged by the dogs for holding the head sheave in one position and other projections 38 and 38' for similarly holding the sheave in a lower position, the weight of the arm 36 being sufficient to normally hold the dogs in engagement with the projections.

A suitable hoisting engine 39 is mounted on the forward portion of the engine car and includes a winding drum 40 provided with a controlling arm 41, and also another winding drum 42 provided with a controlling arm 43. An auxiliary engine 44 is mounted also on the engine car and it is provided with a sprocket wheel 45. The engines obviously may be variously constructed.

A shaft 46 is mounted at a suitable height on the upright frame for supporting pulleys, wheels or the like which may be desired. A winding drum 47 is rotatably mounted on the shaft and has flanges 48 and 49, one end of the drum having a transversely arranged locking key 50 projecting therefrom, the drum having a bore 51 therein. A bull wheel is provided for driving the drum and preferably comprises a channel iron bar 52 that has an axial bore 53 in its middle portion to receive the shaft 46, the bar being adapted to constitute a hub portion and two arms of the wheel. The channel of the bar receives the key 50 and is secured thereto by means of bolts 54 and 54'. Two other arms of the wheel 55 and 56 are formed also of channel iron and are secured to the bar 52 by means of angle irons 57 and 57'. The arms of the wheel are secured to the flange 48 by means of bolts 58 and 58'. A rim 59 having flanges 60 and 61 is secured to the ends of the arms by means of angle irons 62, 62', the rim being formed of bent channel iron of suitable width. A grooved driving wheel 63 having a sprocket wheel 64 connected thereto is rotatably mounted also on the shaft 46 and the sprocket wheel is connected by means of a chain belt 65 with the sprocket wheel 45 of the auxiliary engine.

In order that the tail sheave for guiding the hoisting cable may be in company with the excavating implement as the latter descends with the deepening of the trench, the tail sheave is mounted on a reach-arm which preferably comprises two bars 66 and 67 suitably spaced apart or offset to permit the excavating implement to pass between them, the bars being connected with a hinge bar 68 that is suitably supported, as by the engine car, preferably on the braces 19 and 19'. The bars are relatively long so as to

- reach a considerable distance from the engine car and on the farther end thereof a tail sheave 69 is mounted, the end of the reach-arm being preferably provided with 5 runners 70, 70' adapted to slide on the ground when the engine car is moved ahead. The reach-arm is provided with a guide roller 71 that extends across the open space between the two bars thereof.
- 10 A shoveling or scraping type of excavating implement commonly known as a drag bucket 72 is preferably employed and it has an open forward end 73 adapted for scraping or shoveling, and a back 74 for 15 carrying the earth up from the trench, a bail 75 being pivotally connected to the rearward portion of the sides of the implement by means of trunnions 76, the sides of the implement having lugs 77 thereon to 20 engage the bail for preventing the forward end of the implement from tilting forward and also gouging too deeply into the ground. The back or rear end of the implement is provided with an eye 78 for drawing 25 it back into the trench. A cable 79 is connected to the winding drum 40 of the hoisting engine and is connected to and wound about the bull wheel 59 and preferably extends over and is guided on a sheave 30 mounted on a shaft 81 that is supported by the upright frame above the shaft 46. The cable is wound upon the drum 40 on being unwound from the bull wheel. A hoisting cable 82 is connected to the winding 35 drum 47 and extends upward and over a guide sheave 83 that is mounted on the shaft 81, the cable extending thence upward and over the guide sheave 25 and thence downward under the head sheave 32 and 40 through the reach-arm in contact with the under portion of the roller 71, the cable being connected to the bail 75 or forward portion of the excavating implement. A reversing or returning cable 84 is connected 45 to the winding drum 42 and is guided out of the way of the head sheave frame on a guide sheave 85 mounted on a shaft 86 that is supported by the upright frame below the shaft 46, the cable extending thence 50 through the reach-arm in contact with the under portion of the roller 71 and thence about the guide sheave 69 and is connected to the eye 78 on the rear end of the excavating implement, so that the implement 55 may be dragged back on its bottom and not be lifted from the ground, the implement therefore being prevented from turning over and requiring an attendant to right it. The cable 84 is wound upon the winding 60 drum of the engine when returning the dumping bucket into the trench and is unwound when the bucket is moving forward.
- 65 Preferably a trestle of considerable length is employed and when desired it preferably comprises a suitable number of bents, each comprising a horizontal beam or cap 87 to which two legs 88 and 89 are secured and braced by suitable means, the legs being provided with flange wheels 90 and 90' respectively that are mounted on 70 the track rails 9 and 9' respectively. Two track rails 91 and 92 are mounted upon the plurality of bents and secured to the cap beams by means of angle irons 93 and 93' respectively, the track rails being secured 75 to the intermediate posts 17 and 17' respectively upon the transverse beam 21, the rails being secured also to the guide bars 22 and 22' respectively. Thus a unitary structure is formed of the engine car and 80 the trestle. The portions of the track rails that reach from the upright frame of the engine car to the nearest one of the bents have reinforcing bars 94 and 94' secured to the outer sides thereof. A suitable number of cross bars 95 are secured to the under sides of the track rails 91 and 92 and extend outwardly beyond them, and two arms 96 and 97 are secured also to the track rails and the reinforcing bars thereof respectively. The legs of the trestle bents are provided with oblique angle braces 98 and 99 that are adjustably connected to the lower portions of the legs and are suitably secured to the cross bars 95 next adjacent 95 thereto, two of the braces being secured to the arms 96 and 97 respectively, preferably so as to provide for variation of the effective length of the braces when the trestle is used on an inclination. Each brace is secured to the trestle leg by means of a bolt 100, the leg having a suitable number of bolt holes 101, 102 and 103 therein to receive the bolt. The braces are connected to the bars 95 by means of bolts 104, 104', 105 the braces having a suitable number of holes 105, 106 to receive the bolts which are inserted in the intermediate ones of the holes when the trestle is horizontal, and the bolts 100 are inserted in the intermediate holes 110 in the trestle legs when the latter are vertical. Various adjustments may be made as illustrated in Fig. 12 for inclinations of the track rails of the trestle, the trestle legs remaining vertical so as to directly support 115 the loads on the trestle.
- 120 A suitable tail block 107 is mounted on the end portion of the trestle and supports a tail sheave 108. A dumping conveying car preferably employed comprises a main frame 109 provided with flange wheels 110, 110' that are mounted on the track rails 91 and 92, and the forward end of the frame is provided with a horizontal transversely arranged roller 111, the rear end of the frame 125 preferably having a relatively high portion 112. The main frame is provided near its middle portion with a shaft 113 on which a dumping body frame 114 is tiltingly mounted so that the rear portion thereof to- 130

ward the tail block is somewhat heavier than the forward portion, and the rear portion preferably is provided with a laterally extending end bar 115. The car body has a 5 flat main portion extending forward of its pivotal shaft, and a back 117 that is inclined. A weight 118 preferably is placed behind the back for counterbalancing the body of the car. A load on the forward portion of 10 the car body causes the latter to tilt and dump the load, but premature dumping is prevented by a suitable latch which preferably comprises projections 119 on the sides of the main frame of the car engaged by 15 hooks 120 preferably provided with projections 121 and connected to the car body by means of pivots 122. The trestle is provided with inclined bars 123, 123' at a suitable position for unloading and the projections 20 121 are brought into contact therewith to move the hooks from the projections 119 and permit the car body to tilt and discharge its load. After the hooks are moved to permit the dumping, in case the load is 25 not so placed as to cause tilting of the car body by force of gravity, the car may move farther until the end bar 115 rides on the inclined bars 123, 123' and causes tilting of the body. A cable 124 is wound a number 30 of times about the driving wheel 63 and extends upward and over a guide sheave 125 that is mounted on the shaft 81, the cable extending thence about the tail sheave 108, the end portion 126 of the cable being connected to the rear end of the main frame 109 of the car. The cable extends also downward from the driving wheel and under a guide sheave 127 that is mounted on the shaft 86 and thence to the forward end of 40 the car, the remaining end 128 of the cable being connected to the car at one corner thereof.

Preferably a chute 129 is provided to receive the earth and convey it to one side of 45 the trench, especially when beginning the excavation, the chute having a telescoping receiving portion 130 that may be moved over to receive the earth from the excavating bucket, or may be slipped to one side of the track to permit the conveying car to advance 50 and receive the loads.

It should be understood that various modifications in structure may be made, it being desirable at times to omit the trestle and 55 operate the conveying car on the level of the ground track.

In practical use the reach-arm rests upon the ground surface when beginning an excavation and as the trench is deepened the reach-arm automatically descends and remains on the bottom of the trench and permits the drag bucket to be worked under it advantageously. The hoisting engine is controlled in a well-known manner so as to

wind up the cable 82 which draws the drag 65 bucket up through the reach-arm and brings the bail 75 in contact with the shoulders 33 of the head sheave frame, the latter being adjusted to a suitable position, somewhat as indicated by dotted lines in Fig. 5. As the 70 bucket ascends to be dumped the bail actuates the arm 36 to release the dogs and the frame is carried upward by the bail and holds the bail in proper position for dumping as in Fig. 5. When the bucket is in 75 proper position for dumping, the conveying car is moved forward so that its roller 111 is brought into contact with and prevents the car frame from having injurious contact with the return cable 84, the cable being deflected directly by the roller, as shown in Fig. 5 so as to cause the bucket to tilt and discharge its load onto the conveying car, after which the car is run out to the proper position for discharging the load into the 80 trench, the dumping being accomplished as herein-before described. The drag bucket is returned to the trench by the cable 84 and when the bucket descends it will be understood that the head sheave 32 also descends 90 until stopped by the cable 82 which assumes an angular position, the dogs 35 automatically acting to latch the frame of the sheave in the desired normal position for guiding the cable when operating the excavating implement. It will be observed by reference to Fig. 1 that in case of necessity the sewer braces 7 may be applied early in the operations and not interfere with the operation of the scraping implement, it being permissible to place the braces above the reach-arm. 95

The improved adjustable trestle herein described forms the subject-matter of a divisional application for Letters Patent, filed November 20, 1913, Serial Number 802,074. 100

Having thus described the invention, what is claimed as new is—

1. Excavating apparatus including a movable structure, a guide sheave mounted on a relatively high portion of the structure, a head sheave provided with a relatively low adjustable support, an excavating bucket, and a hoisting cable connected to the bucket and extending over the guide sheave and under the head sheave and enabling the bucket when hoisted to adjust the head sheave. 110

2. Excavating apparatus including a movable structure, a guide sheave mounted on a relatively high portion of the structure, a reach-arm hinged to the structure and extending thereunder for sliding support, a tail sheave mounted on the reach-arm, an excavating bucket to operate under the reach-arm, a hoisting cable extending over the guide sheave and connected to the bucket for hoisting the bucket from under the reach-arm, and a return cable extending about the 120 125

tail sheave and connected also with the bucket for drawing the bucket back under the reach-arm.

3. Excavating apparatus including a movable structure comprising supporting legs, a guide sheave supported on the structure, a reach-arm having pivotal connection with and extending under the structure to move up or down between the legs or to a depth 10 below the plane of the foot of the legs, the end portion of the reach-arm being constructed as a runner to slide on the ground, a tail sheave mounted on the reach-arm, a bucket, a hoisting cable extending over the 15 guide sheave and connected to the bucket, and a cable connected to the bucket and extending about the tail sheave.

4. Excavating and conveying apparatus including a winding engine, a trestle, an excavating bucket, cables connected with the engine and the bucket, a tail sheave movably supported under the trestle to be raised or automatically lowered and guiding one of the cables for returning the bucket 25 under the trestle, the remaining cable acting to draw the bucket from beneath the trestle, and an adjustable guide sheave for the remaining cable controlled by the bucket.

5. Excavating apparatus including a movable structure comprising an openwork supporting portion, and also an upwardly extending frame having a head sheave frame movably mounted thereon, the supporting portion having a tail sheave mounted there- 35 in to move downward below and also with the supporting portion, a guide sheave mounted upon the frame, a head sheave mounted on the head sheave frame, a cable extending over the guide sheave and under 40 the head sheave, a bucket connected to the cable, the bucket controlling the head sheave frame, and a cable extending about the tail sheave and connected to the bucket.

6. Excavating apparatus including a movable structure, cable-operating means on the structure, a guide sheave supported relatively high on the structure, an excavating implement, a guide roller and also a tail sheave operatively supported by the lower 50 portions of the structure, the tail sheave being arranged farther than the roller from the cable-operating means, a hoisting cable connected with the cable-operating means and the implement and extending over the 55 guide sheave, the cable and the implement passing under the guide roller, and a return cable connected to the implement and extending about the tail sheave and under the guide roller.

60 7. Excavating and conveying apparatus including an engine car, an open trestle connected to the car, an open reach-arm hinged to the car and extending adjustably under the trestle, an excavating bucket to operate under and through and by the guidance of

the reach-arm, means coöperating with the engine car for hoisting the bucket up through the reach-arm and the trestle, and adjustable guiding means on the car for the hoisting means controlled by the bucket. 70

8. Excavating and conveying apparatus including a movable structure, an open reach-arm hinged to the structure and extending thereunder for sliding support, an excavating bucket to operate under and by 75 the guidance of the reach-arm, a controllable guide adjustably mounted on the structure, and means coöperating with the structure and the guide for hoisting the bucket up through the reach-arm to discharge its load, 80 the bucket controlling the guide.

9. Excavating and conveying apparatus including a winding engine, a trestle, an excavating bucket, an open hinged reach-arm provided with a supporting runner and extending under the trestle, a tail sheave mounted on the reach-arm, a hoisting cable connected with the engine and the bucket, means for guiding the cable to hoist the bucket through the reach-arm, and a return 85 cable connected with the engine and the bucket and extending about the tail sheave. 90

10. Excavating apparatus including an engine car, a winding engine on the car, an open reach-arm hinged to and extending 95 from the car, a tail sheave supported by the reach-arm, a roller mounted in the open reach-arm, and two cables connected with the engine and extending through the reach-arm in contact with the roller, one of the 100 cables extending about the tail sheave, and an excavating bucket connected to the cables to be hoisted through the reach-arm by the other one of the cables.

11. Excavating apparatus including an 105 engine car provided with vertical guides, a guide sheave supported by the guides, a frame movably guided by the guides and having a head sheave thereon, a winding engine on the engine car, a supported tail 110 sheave, a drag bucket, a hoisting cable connected with the winding engine and to the forward end of the bucket, the cable extending over the guide sheave and under the head sheave, and a reversing cable connected also with the engine and the rear end of the bucket and extending about the tail sheave. 115

12. Excavating apparatus including a structure movably supported on the ground, a winding engine on the structure, an open reach-arm hinged to the structure and extending to the ground for support, the reach-arm being provided with a runner to slide on the ground, a tail sheave supported on the reach-arm, an excavating bucket to operate under the reach-arm, a hoisting cable connected with the engine and the bucket for hoisting the bucket through the reach-arm, and a return cable connected also 125 130

with the engine and the bucket and extending about the tail sheave.

13. Excavating apparatus including an engine car, a sheave frame connected to the car to move upward or downward, a guide sheave mounted on the car above the sheave frame, a head sheave mounted on the sheave frame, latching means for temporarily holding the sheave frame in lowered position, an excavating bucket, a bail connected to the bucket, a winding engine on the car, and a hoisting cable connected with the engine and extending over the guide sheave and under the head sheave and connected to the bail for hoisting the bucket, the bucket on being hoisted automatically releasing the latching means and hoisting the sheave frame ahead of the bucket.

14. Excavating apparatus including an engine car provided with a head sheave and also a tail sheave that are adjustably mounted thereon to descend by gravity, a winding engine mounted on the engine car, a drag bucket, a guide sheave mounted on the engine car at a greater height than the head sheave, a hoisting cable connected with the engine and the forward end of the bucket and extending over the guide sheave and under and in contact with the head sheave, the bucket operating to elevate the head sheave, and a reversing cable connected also with the engine and the rear end of the bucket and extending about the tail sheave.

15. Excavating and conveying apparatus including a structure having an upright guide, a sheave frame movably guided by the guide and adapted for engagement of a bail therewith to prevent shifting of the bail relative thereto, a head sheave mounted on the frame, a guide sheave supported by the upper portion of the structure, a drag bucket, a bail pivoted to the bucket, a winding engine, a hoisting cable connected with the engine and extending over the guide sheave and under the head sheave, the cable being connected to the bail for hoisting the bucket, the bail being movable into contact with the sheave frame for preventing rotation of the bucket and for moving the frame upward to clear the bucket, a return cable connected with the engine and also with the rear end of the bucket, means for guiding the return cable, a conveying car movably supported and having a roller thereon presented toward the return cable when the cable is carried up with the bucket, and means for forcibly moving the conveying car and causing the roller to flex the cable for tilting the bucket in the bail to discharge the load from the bucket onto the car.

16. Excavating and conveying apparatus including an engine car having two upright guides, a guide sheave supported by the upper portion of the guides, a sheave frame movably guided by the two guides and hav-

ing shoulders, a head sheave mounted on the frame, a drag bucket, a bail pivoted to the bucket, a winding engine on the engine car, a hoisting cable connected with the engine and extending over the guide sheave and under the head sheave, the cable being connected to the bail for hoisting the bucket, the bail being movable into contact with the shoulders of the sheave frame for moving it upward to guide the bucket, track rails supported on a plane below the hoisted position of the bucket, a return cable connected with the engine and also with the rear end of the bucket, means for guiding the return cable, a conveying car on the track rails and movable to the return cable, and means for forcibly moving the conveying car to flex the return cable for tilting the bucket in the bail to discharge the load from the bucket onto the conveying car.

17. In excavating apparatus, the combination of an engine car comprising an upright frame, two guide bars mounted uprightly on the car and connected to the frame, a guide sheave supported by the guide bars, a sheave frame having two slides movably mounted in the two guide bars, a head sheave mounted on the sheave frame, a hoisting cable extending over the guide sheave and down and under the head sheave, and an excavating implement connected to the cable and movable thereby into contact with the sheave frame for elevating the head sheave.

18. In excavating apparatus, the combination of an engine car comprising an upright frame, two guide bars mounted uprightly on the car and connected to the frame, a guide sheave supported by the guide bars, two track rails secured to the upright frame and extending past the outer sides of the guide bars, a hoisting cable extending over the guide sheave, a car movable on the rails toward or from the guide bars, means for operating the cable, an excavating implement connected to the cable, a sheave frame mounted on the guide bars to ascend or descend between the two track rails, means for temporarily latching the sheave frame in lowered position, and a head sheave carried on the sheave frame and guiding the cable between the two track rails.

19. The combination of a structure adapted for forward movement, a reach-arm hinged to the structure and extending rearward and downward under the structure, the end of the reach-arm being adapted for sliding support at various depths below the plane of the bottom of the structure, a tail sheave mounted on the reach-arm under the structure, a drag bucket adapted for operation under the reach-arm, a winding engine mounted on the structure, a cable connected with the engine and the forward

end of the bucket for drawing the latter out from under the reach-arm, and a cable connected with the engine and extending over the tail sheave and thence under the 5 sheave and the reach-arm and to the rear end of the bucket and connected thereto.

20. In excavating apparatus, the combination with an engine car, and two cables guided on the car, of an excavating implement connected to the two cables, a reach-arm comprising two bars pivotally connected to the engine car, two runners secured to and supporting the free ends of the two bars, a roller supported between the two 10 bars and guiding the cables, and a tail sheave mounted on the ends of the bars and guiding one of the cables.

21. In excavating and conveying apparatus, the combination with two track rails, 20 an upright frame, a guide sheave mounted upon the frame, and an excavating bucket, of a conveying car movable on the track rails and having a roller on the forward end thereof, a hoisting cable extending over 25 the guide sheave and connected to the bucket for hoisting the bucket toward the sheave, a return cable connected to the bucket and carried to suspended position by the hoisted bucket, means for guiding the 30 return cable, and a cable connected to the conveying car to forcibly draw the roller against and flex the return cable for tilting the bucket.

22. In excavating apparatus, the combination with a frame structure, cable-operating means on the structure, a guide sheave supported relatively high on the structure, a tail sheave adjustably supported under the 35 structure, and an excavating bucket, of a head sheave frame adjustably mounted on the structure, a head sheave mounted on the head sheave frame, a latch for temporarily holding the sheave frame in relatively low 40 position, a hoisting cable connected with the cable-operating means and the bucket and extending over the guide sheave and under the head sheave, and a return cable connected with the cable-operating means and the bucket and extending about the tail 45 sheave.

23. In excavating and conveying apparatus, the combination with two surface rails, an engine car, and a trestle comprising bents movable on the rails, of a reach-arm 50 pivotally connected to the engine car and extending away and downward at an inclination under the trestle bents and movable pivotally to extend below the plane of the rails, means independent of the engine car 55 for supporting the end of the reach-arm, a hoisting cable, an excavating bucket connected to the cable to be drawn thereby upward from beneath the reach-arm, a return cable connected to the bucket for drawing 60 the bucket under and toward the end of the

reach-arm, and a tail sheave mounted on the far end of the reach-arm and guiding the return cable.

24. In hoisting apparatus, the combination with a frame structure, cable-operating means on the structure, a guide sheave supported relatively high on the structure, and an excavating bucket, of a relatively long reach-arm hinged relatively low on the structure and having a guide roller thereon, a tail sheave mounted on the reach-arm beyond the roller, a return cable extending about the tail sheave and connected with the bucket for drawing the latter under the reach-arm, the cable and the bucket passing 70 under the roller, and a hoisting cable connected with the cable-operating means and the bucket and extending over the guide sheave for drawing the bucket from under the reach-arm and hoisting it toward the 75 guide sheave, the hoisting cable and the bucket passing under the guide roller.

25. In hoisting apparatus, the combination with a frame having a cable guide, cable-operating means, and an excavating 80 bucket, of a reach-arm hinged to and extending downward at an inclination under the frame, a tail sheave mounted on the end portion of the reach-arm, a guide roller connected with the reach-arm between the support of the reach-arm and the tail sheave, a return cable extending about the tail sheave and connected with the bucket, and a hoisting cable connected with the bucket 85 and the cable-operating means and guided by the cable guide to be guided by said roller for drawing the bucket under the reach-arm and the roller and thence upward.

26. In hoisting apparatus, the combination with a frame structure, cable-operating means on the structure, a guide sheave supported relatively high on the structure, a tail sheave having a carrying frame adjustably supported at a distance from and relatively lower than the guide sheave, the frame extending from its support downwardly, and a bucket, of a return cable extending about the tail sheave to be variably guided thereby and connected with the 105 bucket, a movable frame guided on the structure, a head sheave mounted on the movable frame, and a hoisting cable connected with the cable-operating means and the bucket and extending over the guide 110 sheave, the hoisting cable extending under and in contact with the head sheave and in action hoisting or lowering the movable frame with the bucket.

27. In excavating apparatus, the combination with two surface rails, two stands of sheathing in planes between the rails, a brace horizontally arranged between the two stands of sheathing, and a structure movable on the rails above the sheathing, of a 120 125

65

- reach-arm pivotally connected to the structure and extending thereunder and also under the brace for sliding support between the two stands of sheathing, a tail sheave 5 mounted on the reach-arm, a winding engine on the structure, a drag bucket, a return cable connected with the engine and extending about the tail sheave, the cable being connected to the rear end of the bucket 10 for drawing the bucket under the reach-arm, and a hoisting cable connected with the engine and the forward end of the bucket for drawing the bucket forward under and also out from under the reach-arm.
- 15 28. In hoisting apparatus, the combination with a frame structure, cable-operating means on the structure, a guide sheave supported on the upper portion of the structure, a tail sheave supported at a distance 20 from and variably relatively lower than the guide sheave, and an excavating bucket, of a return cable extending about the tail sheave to be variably guided thereby and connected with the bucket, a sheave frame 25 slidably guided vertically to move up or down on the structure, a head sheave mounted on the sheave frame, and a hoisting cable connected with the cable-operating means and the bucket and extending over 30 the guide sheave and under and in contact with the head sheave to hoist the sheave frame with the bucket.
29. In hoisting apparatus, the combination with a frame structure, cable-operating 35 means on the structure, and a bucket, of a hoisting cable connected with the cable-operating means and the bucket, means on the structure for guiding the cable to hoist the bucket, a return cable connected to the 40 bucket and carried upward by the hoisted bucket, a guide for the return cable, means for operating and controlling the return cable, and means for flexing the upper portion of the return cable to tilt the hoisted 45 bucket.
30. In excavating and conveying apparatus, the combination of a frame structure, cable-operating means, an excavating dumping bucket, a hoisting cable connected with 50 the cable-operating means and the bucket, means on the structure for guiding the cable to draw and hoist the bucket, a return cable connected with the bucket and carried upward by the hoisted bucket, a guide 55 for the return cable, means for operating and controlling the return cable, a car movable on the structure to the return cable under the hoisted bucket, and means enabling the car to force the carried-up portion of 60 the return cable and deflect the same for dumping the load of the bucket onto the car.
31. In excavating and conveying apparatus, the combination of a frame structure, cable-operating means, an excavating dumping 65 bucket, a hoisting cable connected

with the cable-operating means and the bucket, means on the structure for guiding the cable to draw and hoist the bucket, a return cable connected with the bucket and carried upward by the hoisted bucket, a tail 70 sheave supported for vertical adjustment under the structure and guiding the return cable, means for operating and controlling the return cable, and means coöperating with the structure and acting on the hoisted 75 bucket for dumping a load from the bucket.

32. In excavating apparatus, the combination of an engine car, two upright guides supported by the engine car, a head sheave frame movably guided by the guides and 80 carrying a head sheave, a hoisting engine on the engine car, a drag bucket, a guide sheave mounted on the upper portion of the engine car, a hoisting cable operatively connected with the hoisting engine and the bucket and 85 extending over the guide sheave and under the head sheave, a supported tail sheave, a reversing cable operatively connected with the hoisting engine and the bucket and extending about the tail sheave, and a guide 90 mounted on the engine car on one side of the two upright guides and guiding the reversing cable over laterally to clear the upright guides and the head sheave frame.

33. In excavating and conveying apparatus, the combination of an engine car comprising a platform and an upright frame, two track rails connected to the upright frame and extending therefrom, two upright guides between the two track rails and connected to the lower and upper portions of said upright frame, a head sheave frame movably guided by the guide bars and carrying a head sheave, a hoisting engine on said platform, a drag bucket, a guide sheave 100 mounted on said upright frame above said head sheave frame, a hoisting cable operatively connected with said engine and said bucket and extending over said guide sheave and also under the head sheave, a conveying 105 car movable on the track rails to or from the upright guides, a tail sheave supported above the track rails, a controlling cable extending from said upright frame about said tail sheave and being connected 110 to the conveying car, said controlling cable extending also from said upright frame and being connected to one corner of said conveying car, a winding drum on said engine car for operating said controlling cable, and 115 means mounted on said upright frame guiding said controlling cable over laterally to one side of said upright guides to clear the path of said head sheave frame and said bucket.

34. In excavating and conveying apparatus, the combination of an upright frame having vertical guides, a drag bucket and a conveying car operative on one side of the frame and movable toward or from the 120

guides, a hoisting cable guided on the upper portion of the frame and connected to the bucket for hoisting the bucket adjacent to the guides, a frame movably guided by the 5 guides and carrying a sheave for guiding the cable, power means beyond the opposite side of the frame for operating the cable, a winding drum also on the opposite side of the frame, a returning cable connected 10 with the power means and the bucket, a tail sheave for guiding the returning cable, a controlling cable connected to opposite ends of the conveying car and also with said drum, a tail sheave for guiding the controlling 15 cable, and a series of means mounted on the upright frame for guiding the returning cable and the controlling cable about one side of the upright guides and the path of the bucket.

20 35. In excavating and conveying apparatus, the combination of an upright frame, two guide bars vertically supported by the frame, a guide sheave mounted on the up-

per portion of the frame, supported hoisting means, a head sheave frame movably 25 guided by the two guide bars and carrying a head sheave, a hoisting cable connected to the hoisting means and extending over the guide sheave and under the head sheave, a drag bucket connected to the cable to be 30 hoisted thereby, the bucket on being hoisted engaging and hoisting the head sheave frame, and movable latching means constructed to coöperate with said upright frame and said head sheave frame for latching the head sheave frame in lowered position, said latching means being engaged by said bucket on being hoisted for releasing 35 said head sheave frame.

In testimony whereof, I affix my signature 40 in presence of two witnesses.

JOSEPH L. POTTER.
